UNITED STATES PATENT OFFICE.

JOHN R. TILLMAN, OF BRIDGEPORT, CONNECTICUT, ASSIGNOR, BY MESNE ASSIGNMENTS, TO LOCOMOBILE COMPANY OF AMERICA, INCORPORATED, OF NEW YORK, N. Y., A CORPORATION OF NEW YORK.

OILING SYSTEM.

Application filed March 15, 1918. Serial No. 222,527.

This invention relates to oiling systems for engines, and is more especially concerned with an oil pump having special application to internal combustion engines of 5 the class in which oil is drawn from the lower portion of a crank case, and is discharged through conduits leading to various bearing surfaces.

My invention will be best understood by 10 reference to the following description, when taken in connection with the accompanying drawings of one specific embodiment thereof, while its scope will be more particularly pointed out in the appended claims.

15 In the drawings:

Fig. 1 is a vertical, cross-sectional view of a portion of the crank case of an engine equipped with an oiling system having an oil pump embodying my invention;

20 Fig. 2 is a sectional view on line 2—2 of Fig. 1; and

Fig. 3 is a sectional view on line 3—3 of Fig. 1.

Referring to the drawings, and to the 25 embodiment of my invention which I have selected for illustration, I have there shown a portion of an engine crank case comprising an upper part 4, and a lower part 5, one separable from the other in a usual and well-known manner. The upper part is 30 provided with a usual main oil duct 6, and a plurality of branch ducts 7 and 8, for supplying bearing surfaces which it is unnecessary here to show or describe.

35 Supported by the upper part of the crank case, and depending into its lower part, is an oil pump which is so arranged as to make it possible to remove either the pump or the lower part of the crank case without disturbing the other. To this end, I 40 have herein provided the lower part of the crank case with an opening 9 for the removal of the pump, and have provided a closure 10 normally to close said opening.

45 Preferably the latter is in the bottom of the crank case, and the pump is of a vertical type, so that the latter may be withdrawn in a downward direction from the crank case. The closure 10 may be, and is herein, 50 provided with a depression 11, constituting a well, from which the pump draws its supply, it being understood, of course, that the oil, after passing through the system

to the bearings, gravitates back to this well, where it is again taken by the pump. The 55 plate 10 is herein in the form of a circular cover, having its flange 12 perforated to receive suitable fastening means, herein comprising a plurality of cap-screws 13. A gasket 14 may be interposed between the 60 cover-plate and the crank case to ensure a non-leaking joint.

The pump may be of any suitable type, but in the present example, I have shown 65 a gear pump, comprising a pair of fluid-propelling gears 15 and 16, operating in a well-known manner to draw the oil from the source of supply, and to discharge the same into the passages leading to the bearing surfaces. These gears may be driven by 70 any suitable means, but in the present example, the gear 15 is provided with a shaft 17, which extends in an upward direction through the lower part 5 of the crank case to the upper part 4, where it is provided with suitable driving means, which may include a gear 18. The gear 16, which is driven by the gear 15, may be provided with a short shaft 19.

The pump may be provided with any suitable form of housing, but in the present instance, I have shown a pump housing comprising a plurality of parts, including two caps 20 and 21, and an intermediate gear casing 22, the latter being provided 85 with an intake passage 23, through which the oil is drawn by the gears 15 and 16. The gear casing is also provided with a discharge passage 24, best shown in Figs. 2 and 3, which receives the oil from the gears, and discharges the same into a discharge chamber 25, formed in the cap 21. The gear casing 22 may be, and is herein, provided with a boss 26, forming a bearing for the shaft 17, and a second boss 27, forming a 90 bearing for the shaft 19. Preferably both bosses extend into the chamber 25, and preferably the boss 26 is extended into, and fits, an opening 28, provided in the cap 21, as best shown in Fig. 1. The two caps and the interposed gear casing may be secured together by a plurality of screws 29, passing through all three of these parts, and preferably threaded into the upper cap 21, so that the screws may be removed in a 100 downward direction, and the internal parts

of the pump rendered accessible for inspection and repair, without the necessity of removing the entire pump.

The pump may be provided with any appropriate discharge passage, communicating in any suitable way with the ducts leading to the bearing surfaces, but in the present example, a discharge passage 30 is formed by providing the cap 21 with an integral, 10 tubular extension 31, which also forms a housing for the shaft 17, and is provided at its upper end with a bearing 32 for said shaft. An inner housing 33, preferably in the form of a tube, connects the bearings 15 and 32, and is interposed between the passage 30 and the shaft 17, thereby preventing the escape of oil in an upward direction through the bearing 32.

Any suitable arrangement may be provided 20 for communication between the discharge passage 30 and the duct 6, but in the present example, the latter extends laterally into a vertical bore 34, into which the tubular extension is snugly fitted, said extension 25 being provided with a lateral port 35, registering with the adjacent end of the duct 6. Thus it is possible to remove and replace the pump, and to connect and disconnect the 30 passages by simply sliding the tubular extension 31 in a vertical direction in the bore 34.

As a means for securing the pump to the upper part 4 of the crank case, I have herein provided the tubular extension 31 with a 35 flange 36, to receive a plurality of screws 37, by means of which said flange may be secured to the under side of the upper part 4. These screws may be rendered accessible for the purpose of removing the pump, without 40 disturbing the lower part 5 of the crank case, by providing the latter with a lateral aperture 38, normally closed by a cover-plate 39, secured in its place by screws 40. By simply removing this plate, a wrench or 45 screw-driver may be introduced to effect the removal of the screws 37. Thus it is evident that, by removing the cover-plates 10 and 39, the pump may be dismounted as a unit, without disturbing the lower part 5 of the 50 crank case. It is also evident that, since the pump is supported by the upper part of the crank case, the lower part may be removed without disturbing the pump.

Preferably, the pump depends into the 55 aperture 9, and is separated from the margin of the latter by a space sufficient to permit oil to gravitate into the depression 11. By making the pump extend through the aperture 9 into the depression 11, removal 60 of the cap 10 renders the lower end of the pump readily accessible, without the necessity of reaching into said aperture. Preferably, the pump is provided with a suitable screen 41, which may be, and in the present example is, in the form of a perforated cyl-

inder encircling the pump body, and provided at its lower end with a cap 42, which is secured to the cap 20 by a screw 43. By first removing the cap 10, and then the screw 43, the screen 41 may be withdrawn in a 70 downward direction and cleaned, without disturbing anything else. If further inspection is necessary, the screws 29 may then be removed, and the cap 20 taken off, thereby exposing the gears 15 and 16, which may also be removed for inspection or repair, without disturbing the remaining parts of the pump. The advantage of these features will be readily appreciated.

While I have herein shown and described 80 one specific form or embodiment of my invention, and have disclosed and discussed in detail the construction and arrangement incidental to one specific application thereof, it is to be understood that my invention is 85 limited neither to the mere details or relative arrangement of parts, nor to its specific embodiment herein shown, but that extensive deviations from the illustrated form or embodiment of the invention may be made, 90 without departing from the principles thereof.

Having thus described one form of my invention, what I claim and desire by Letters Patent to secure is:

1. In an oiling system for engines, the combination of a casing having an opening, a pump disposed within said casing and having a strainer, said pump and its associated parts being bodily removable through said opening and said strainer being individually removable through said opening, and a closure for said opening.

2. In a gear pump, the combination of a 105 housing comprising a plurality of parts including two caps and an intermediate gear casing, said gear casing being provided with an intake chamber, and one of said caps being provided with a discharge chamber, means to secure said parts together, and a 110 pair of cooperating fluid-propelling gears housed in said gear casing, said gears having shafts extending from said casing into said cap which is provided with a discharge chamber, one of said shafts terminating 115 within said discharge chamber.

3. In a gear pump, the combination of a 120 housing comprising a plurality of parts including two caps and an intermediate gear casing, said gear casing being provided with an intake chamber, and one of said caps being provided with a discharge chamber, means to secure said parts together, and a 125 pair of cooperating fluid-propelling gears housed in said gear casing, said gears having shafts extending into said cap which is provided with a discharge chamber, one of said shafts terminating within said discharge chamber, and an inner housing for 130 the other of said shafts.

4. In a gear pump, the combination of a housing comprising a plurality of parts including two caps and an intermediate gear casing, said gear casing being provided with
5 an intake chamber and having a projecting boss, and one of said caps being provided with a discharge chamber and an opening to receive said boss, means to secure said parts together, and a pair of cooperating fluid-propelling gears, one of which is provided 10 with a shaft having a bearing in said boss.

In testimony whereof, I have signed my name to this specification.

JOHN R. TILLMAN.
